(57) CLAIM

The ornamental design for a display screen portion with icon, as shown and described.

DESCRIPTION

The single FIGURE is a front view of a display screen portion with icon showing my new design.

The dot-dash broken line illustrates the portion of the display screen which forms no part of the claimed design. The evenly-spaced broken line illustrates an unclaimed portion of the icon and forms no part of the claimed design.

1 Claim, 1 Drawing Sheet
